UNITED STATES PATENT OFFICE.

WILLIS E. LA RUE, OF INDIANAPOLIS, INDIANA, ASSIGNOR OF ONE-HALF TO WILLIAM P. HALL, OF INDIANAPOLIS, INDIANA.

FAUCET.

1,351,524.

Specification of Letters Patent. Patented Aug. 31, 1920.

Application filed October 28, 1919. Serial No. 384,051.

To all whom it may concern:

Be it known that I, WILLIS E. LA RUE, a citizen of the United States, and a resident of Indianapolis, county of Marion and State 5 of Indiana, have invented a certain new and useful Faucet; and I do hereby declare that the following is a full, clear, and exact description thereof, reference being had to the accompanying drawings, in which like numbers refer to like parts.

This invention relates to new and useful improvements in faucet constructions primarily adapted to be used in connection with soda fountains and the like for dispensing carbonated water and other liquids under pressure.

The main feature of the invention lies in the valve construction, whereby continued use of the faucet would not wear the valve 20 so as to cause a slight leak therein.

Another feature of the invention is the means, in connection with a valve, for preventing the leakage of the faucet, returning any seepage or leakage to the rear and discharging it into a suitable receptacle.

Another feature of the invention is the provision of branch channels which prevent the escape of liquid from the faucet or any part thereof under its high pressure, causing any such leakage to pass through the 30 branch channels.

Further features of the invention will be more fully set forth hereinafter in the following specification and the accompanying 35 drawings.

In the drawings Figure 1 is a side elevation of the faucet showing the valve handle in closed position. Fig. 2 is a central vertical section through the faucet showing the 40 valve in closed position. Fig. 3 is the same as Fig. 2 showing the valve in position to discharge a large stream. Fig. 4 is the same as Fig. 2 showing the valve in position to discharge a fine stream. Fig. 5 is a cross section taken on the line 5-5 of Fig. 4. Fig. 6 is a side elevation of the valve plunger.

In the drawings there is shown a faucet 10 mounted integral with an extension pipe 50 11 and having a downwardly projecting nozzle 12. The faucet 10 is provided with a central vertical valve chamber 13, having a valve seat at the bottom thereof in which is slidably mounted a close fitting valve plunger 14 having a tapered end on the bottom

thereof adapted to seat in said valve seat, in which position it would close the inlet conduit 15 communicating with the inlet conduit extending through the extension pipe 11. The valve plunger 14 is provided with 60 a passageway 17 extending vertically upwardly from the bottom thereof, and through the periphery, so as to be in position to register with the discharge passage 18 which opens directly into the nozzle 12. 65

The valve plunger 14 is provided with a cap 19 mounted on the top thereof to which is pivoted the arms 20, which are pivotally connected at their lower ends to the lower ends of the arms 21, fulcrumed at 22, so that the movement of the knob handle 23 from front to rear raises the plunger from the valve seat. The first rearward movement of the handle raises the plunger just enough to unseat it and permit the liquid to discharge 70 into the valve chamber and pass through the passage 17 and discharge passage 18 in a broad stream, as shown in Fig. 3. By moving the handle entirely to the rear, as shown in Fig. 4, the plunger is elevated until the passage 17 registers with the reduced discharge passage 24, which extends directly downward and terminates in the reduced nozzle 25, whereby a fine stream 75 will be discharged.

Connected with the passage 18 adjacent the valve chamber there is a drain passage 26 which extends around the valve chamber and communicates with the drain pipe 27 in the extension pipe 11. When the valve is in closed position, as shown in Fig. 2, any possible leakage which may be permitted to escape by the valve will flow slowly through the passage 17 and will be caught by the drain passage 26 and returned through the 80 pipe 27, not having enough pressure or force behind it to carry it over the opening into the passage 26. Whereas when the valve is opened the pressure of the stream will carry it directly to the passage 26 and be discharged through the passage 18, none of which stream would be caught and returned through the drain passage. For preventing any escape of the liquid passing the 85 sides of the valve plunger when it is in open position, there is provided an annular groove 28 about the periphery of the valve chamber 13 which will catch any such leakage and cause it to pass downwardly 90 through the housing of the faucet 10 105 110

through the pasageways 29 into the nozzle 12. This leakage would only occur when the passage was opened and the liquid passing therethrough under high pressure, so that any leakage during this time will be carried right along with the stream through the nozzle, but the valve being closed and no stream being discharged from the nozzle there should not be enough leakage to carry the liquid as high up in the faucet as the groove 28, the passage 26 being lower than 28, preventing any leakage at the top.

The side drain passage 30 extends vertically downward through the faucet 10, as shown in dotted lines, discharging into the nozzle 12, as shown in Fig. 5. This side drain is adapted to gather any leakage which may occur from the passage 17 as the plunger 14 is elevated or lowered between the position shown in Figs. 3 and 4. The leakage from said passageway is caught by the grooves 31 in the periphery of the plunger which communicates with the passage 30.

25. The invention claimed is:

1. A faucet structure having a valve chamber therein with a valve seat, a liquid inlet communicating with said chamber through said valve seat, an outlet communicating with said chamber, a reciprocatory valve plunger adapted to seat in said valve seat having a passage therethrough for opening and closing the communication between said inlet and outlet, and means for preventing leakage from said faucet when said valve is closed.

40. 2. A faucet structure having a valve chamber therein with a valve seat, a liquid inlet communicating with said chamber through said valve seat, an outlet communicating with said chamber, a reciprocatory valve plunger adapted to seat in said valve seat having a passage therethrough for opening and closing the communication between said inlet and outlet, and a by-pass communicating with said outlet for catching any liquid dripping from said plunger passage.

45. 3. A faucet structure having a valve chamber therein, a liquid inlet and outlet communicating with said chamber, a sliding plunger adapted to be slidably operated within said valve chamber having a passage therethrough, a reduced outlet passage communicating with said chamber whereby when said valve is in one position said inlet will be closed and when in another posi-

tion said inlet will communicate with said first mentioned outlet, and when in the third position said inlet will communicate with said reduced outlet, means for carrying any leakage from said faucet when said valve is closed, and means for causing leakage to be discharged through the nozzle when said valve is open.

5. A faucet structure for dispensing liquids having a hollow body portion, an inlet and outlet communicating with said hollow body portion, a reciprocating valve slidably mounted in said hollow body portion whereby in one position the communication between said inlet and outlet will be closed, and in another position will be open, and an annular groove in said body portion surrounding said valve for catching and discharging liquid escaping past said valve.

5. A faucet structure having a valve chamber therein, a liquid inlet and outlet communicating with said chamber, a sliding plunger adapted to be slidably operated within said valve chamber having a passage therethrough, a reduced outlet passage communicating with said chamber whereby when said valve is in one position said inlet will be closed and when in another position said inlet will communicate with said first mentioned outlet and when in a third position said inlet will communicate with said reduced outlet, grooves in the periphery of said plunger and partially surrounding the discharge outlet of the passage therethrough for catching any leakage from said passage when said plunger is between the outlet and inlet passage, and a passageway extending downwardly through said faucet discharging therefrom in communication with said grooves for carrying away the liquid caught therein.

6. A faucet structure having a valve chamber therein, an inlet conduit communicating with a passageway to said valve chamber, a discharge nozzle communicating with said chamber, a valve mounted in said chamber in position to open and close the communication between said inlet and discharge nozzle, and a by-pass communicating with said discharge nozzle adjacent said chamber for catching and leading away any drippings and liquid not under pressure.

In witness whereof, I have hereunto affixed my signature.

WILLIS E. LA RUE.
